UNITED STATES PATENT OFFICE.

OLOF FRANKMAN, OF MÄLMO, SWEDEN.

BEET-HARVESTER AND THE LIKE.

1,366,645.

Specification of Letters Patent. Patented Jan. 25, 1921.

Application filed October 25, 1919. Serial No. 333,338.

To all whom it may concern:

Be it known that I, OLOF FRANKMAN, estate owner, a citizen of the Kingdom of Sweden, and residing at Malmö, Sweden, 5 have invented a new and useful Improvement in Beet-Harvesters and the like; and I do hereby declare the following to be a full, clear, and exact description of the same.

It is already known in beet-harvesters and 10 the like to use elevators for elevating the beets loosened from the ground by means of a pair of shares, and such elevators are placed close behind the shares. If the beets are not growing in a straight line or if they 15 are pushed sidewise by the shares at the loosening they strike the edges of the elevator and just when they are going to be lifted they will fall to the side and remain upon the ground.

20 My present invention has for its object to prevent the tops or beets from dropping down from the elevator and to facilitate the removing of the tops or beets from the elevator at its upper end.

25 The invention is illustrated in the accompanying drawing, in which Figure 1 shows a side view of the elevator and adjacent parts of the machine. Fig. 2 is a rear view of the elevator. Fig. 3 is a plan view of the same 30 and Figs. 4 and 5 show a prong of the forks thereon.

The device for loosening the beets from the ground need not be described in this connection, said device being mounted upon the 35 same truck which carries the elevator. When the beets are to be elevated the machine is driven forward in the direction of the arrow I and the elevator runs in the direction of the arrow II. After loosening 40 the beets are picked up from the ground marked III by means of the elevator. For this purpose a chain elevator provided with forks in a known manner is used, which chain elevator runs over chain wheels 45 mounted on shafts 1 and 2 placed in such a manner that the elevator inclines somewhat backward.

According to my invention the elevator 50 consists of a plurality of endless chains (in the drawing four chains) 3, 4, 5 and 6, all of them being provided with prongs 7, 8, 9 and 10 respectively (Fig. 3). These prongs are placed in such a manner that the prongs 7 and 8 on the two outer chains in the direction of movement always pass somewhat 55 ahead of the prongs 9 and 10 on the inner

chains, and if besides all of the prongs are a little curve shaped as shown in the drawing they form together a shallow cup shaped pitch-fork (compare Fig. 3), in which the 60 beet or the like securely rests during the upward movement. A dropping sidewise is prevented by the higher prongs on the outer chains and if a beet on the ground strikes the edges of the elevator it is pushed to its 65 center because of the location of the prongs referred to above.

A simple method to carry out this device in practice is to use chains of quite the same kind with all the prongs arranged at the 70 same distance in relation to each other. The sprocket or chain wheels are also of the same kind but, before their fixing to the shafts the inner wheels are turned a small angle backward in relation to the outer ones and 75 thereby the correct placing of the prongs is obtained. According to another form of construction all of the prongs are mounted on a broad chain or the like forming an endless belt or mat, which may be perforated if 80 desired. The number of chains and the number of prongs in each pitch-fork may obviously be varied according to requirements.

I have found that the tendency of the 85 beets to be pushed sidewise is greatest when the beets first strike the elevator, i. e. at the lower end of the same and to prevent this during all circumstances it is advisable on the lower elevator shaft to fix a prong wheel 90 at each side of the elevator, said wheels generally speaking enlarging the pitch-forks at the moment when the beets first are picked up from the ground, and such prong wheels are also shown in the drawing. The 95 prongs or arms 11 are all of the same form and length as the prongs 7—10 and the hubs 12 of said wheels are fixed to the shaft 2 and rotate together with the same in such a way that the prongs 11 pass in front of the 100 prongs 7 and 8 on the outer chains when the elevator is turning around the lower shaft and the sprocket wheels placed thereon. Thereby the shallow cup form of the pitch-forks is maintained and they are given an 105 enlarged width.

To prevent earth or the like being packed together between the chains and the sprocket wheels the prongs may be given a special form shown in Figs. 4 and 5. The prongs 110 (for instance 7) at the end connected to the chain are given the form of a fork 13, which

directly forms a link therein and covers the opening for the teeth 14 of the sprocket wheels (Fig. 4).

For removing the tops or beets from the elevator curved bars 15 are fixed at the upper end of the same, said bars being arranged between the chains and provided with eyes surrounding the upper shaft, from which they are bent outward and downward 10 to form a curved bridge, along the upper side of which the tops or beets slide down into a receptacle. The lower ends of said bars are fixed to the framework at the upper end of said receptacle.

Having now described my invention and the manner in which it is to be performed I declare that what I claim is:—

1. A beet-harvester comprising an elevator provided with pitch-forks for raising the beets from the ground said pitch-forks consisting of a number of prongs arranged in such a way that they together form a shallow cup, a prong wheel mounted upon the lower elevator shaft at each side of the elevator, the prongs in said wheels being arranged in such a way that they in the direction of movement of the elevator pass in front of the outer prongs belonging to the pitch-forks mounted on the elevator when 30 said pitch-forks are turning around the lower elevator shaft.

2. A beet-harvester comprising an elevator provided with pitch-forks for raising the beets from the ground said elevator consist-

ing of a plurality of chains, each of which 35 is provided with curved prongs of uniform shape and displaced in relation to each other so that shallow cup shaped pitch-forks are formed, a prong wheel mounted on the lower elevator shaft on both sides of the elevator, 40 the prongs of said wheels being of the same shape as the prongs mounted on the elevator and passing in front of the outer prongs thereon when the pitch-forks of the elevator are turning around the lower elevator shaft. 45

3. A beet-harvester comprising an elevator provided with pitch-forks for raising the beets from the ground, said elevator consisting of a plurality of separate chains each of which is provided with curved prongs displaced in relation to each other so that shallow cup shaped pitch-forks are formed, said prongs at the ends connected to the chains having the form of forks, which directly form links in said chains and cover the 55 openings for the sprocket wheels therein, a prong wheel mounted on the lower elevator shaft at each side of the elevator in such a way that the prongs therein pass in front of the edges of the pitch-forks when they are 60 turning around said lower elevator shaft.

In testimony whereof, I have signed my name to this specification in the presence of two subscribing witnesses.

OLOF FRANKMAN.
